UNITED STATES PATENT OFFICE.

DAVID C. SASSEMAN, OF RIVER FOREST, ILLINOIS, ASSIGNOR TO F. H. SMITH MANUFACTURING COMPANY, OF CHICAGO, ILLINOIS, A CORPORATION OF ILLINOIS.

MAGNETIC PICK-UP FOR RIVETING-MACHINES.

1,079,148.

Specification of Letters Patent. Patented Nov. 18, 1913.

Application filed February 22, 1912. Serial No. 679,349.

To all whom it may concern:

Be it known that I, DAVID C. SASSEMAN, a citizen of the United States, residing at River Forest, in the county of Cook and 5 State of Illinois, have invented certain new and useful Improvements in Magnetic Pick-Ups for Riveting-Machines, of which the following is a specification, reference being had to the accompanying drawings, forming 10 a part thereof.

The purpose of this invention is to provide an improved pick-up device for positioning rivets or like fittings in a riveting machine.

15 It consists of the elements and features of construction described and shown in the drawings as indicated in the claims.

In the drawings:—Figure 1 is a side elevation partly in section of a riveting machine fitted with a device embodying this invention. Fig. 2 is a detail view in section showing a modified form of the device. Fig. 3 is a detail section taken as indicated at line 3—3 on Fig. 2.

20 The riveting machine or hammer shown in Fig. 1 comprises a familiar form of C-shaped frame, A, carrying a clenching anvil, B, on its lower arm and a plunger, C, in its upper arm, mounted for reciprocation toward and from the anvil, B. The upper end of the plunger, C, is provided with a wearing shoe of hard metal, D, upon which the operating cam, E, bears, and against the under side of which a returning spring, 25 F, operates. The body of the plunger C is composed of brass or some other non-magnetic metal and has inserted into its lower end a magnet, G, which constitutes the pick-up device for the rivets which are to be used 30 in the machine. By virtue of a slot, G¹, extending throughout the greater part of the length of the magnet, G, and also by reason of the method of magnetization the said magnet is of the "horse-shoe" or double 35 pole type, having its two opposite poles, G², G², in close proximity but separated by a small air gap at, G³. As will be well understood, the efficiency of this type of magnet is much greater than that of the more 40 usual bar magnet employed for this purpose, in which only one of the poles is put to work; in consequence of this arrangement the entire pulling power of the magnetic 45 force stored in the magnet, G, is exerted 50 upon any object applied to the poles. Pref-

erably though not necessarily, the slot, G¹, is made considerably wider throughout the greater part of its length than in the vicinity of the poles, G², G². This results in an intensification of the magnetic field in the vicinity of the poles by reason of the reduced air gap, G³, at this point which affords the path of least resistance to the passage of the magnetic lines of force as compared with all other possible paths. Although the plunger with its magnet, G, moves in a guide-way of the magnetic iron frame, A, the thickness of the insulating walls, C¹, of the non-magnetic plunger, C, is such that only by traversing the air gap, G³, 70 will the lines of force encounter the minimum of non-magnetic medium. Thus when a steel rivet such as that indicated at, H, is brought within the field of influence of the magnet, G, it is readily and strongly attracted thereby and will remain in contact therewith until the riveting operation is completed. To assist in properly centering the head of the rivet upon the end of the plunger the walls, C¹, of the latter are arranged to extend slightly beyond the end of the magnet poles at, C², the result being a cup-shaped end for the plunger, and if desired the poles of the magnet itself may be cuffed out as indicated at, G⁴, for more accurately engaging rivets which are made with convexly rounded heads. 80

In Figs. 2 and 3 there is illustrated a modified form of magnet which is perhaps theoretically more nearly ideal than that shown in Fig. 1, but which may not always be found so desirable from a constructional standpoint. It is C-shaped in outline so that the space between its arms which corresponds to the space, G¹, in Fig. 1 becomes in this case preferably circular, affording the least possible opportunity for dissipation of the magnetic force by the creation of a magnetic field elsewhere than at the poles. 90 This magnet is shown lodged in a bifurcated plunger of non-magnetic material with a bushing, G⁵, of such material occupying the circular space within the magnet. In this case the frame, A, is cut away sufficiently at, A¹, to prevent contact of the magnet, G, with the frame, A, and to insure a sufficiently wide air gap as compared with the air gap, G³, between the poles. 95 100 105

I claim:—

1. In a riveting machine, the combination 110

of a frame of magnetic metal and a driver guided for movement therein, comprising a two-pole magnet consisting of a bifurcated bar with its poles disposed side by side at the driving end, and a carrier for said magnet of non-magnetic metal constituting a sheath which surrounds the poles of the magnet, the air gap between said magnet poles being less than the shortest possible path connecting them through said non-magnetic sheath.

2. In a riveting machine, the combination of a frame of magnetic metal, and a driver guided for movement therein comprising a carrier of non-magnetic material, and a two-pole magnet consisting of a bifurcated bar with its poles disposed side by side at the bifurcated end, the space between the two limbs being least in the vicinity of said poles and such magnet being secured in a socket in the end of the carrier with its poles exposed.

3. In a riveting machine, a driver com-

prising a carrier of non-magnetic material, and a two-pole magnet secured therein having its poles disposed side by side at the driving end, the material of the carrier extending alongside the said poles and slightly beyond them.

4. In a riveting machine the combination of a frame of magnetic metal and a driver guided for movement therein, comprising a carrier of non-magnetic material, and a two-pole magnet consisting of a bifurcated bar with its poles disposed side by side at the driving end, said magnet being slightly sunk in the end of the carrier to permit protrusion of the non-magnetic material thereof beyond the poles of the magnet.

In testimony whereof I have hereunto set my hand at Chicago, Illinois, this 20th day of February, 1912.

DAVID C. SASSEMAN.
